Primary Examiner — Richard Kearney*Assistant Examiner* — Benjamin M Weeks(57) **CLAIM**

The ornamental design for a telescope, as shown and described.

DESCRIPTION

FIG. 1 is a front perspective view of a telescope showing my new design;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view thereof in used; and,

FIG. 10 is an enlarged detailed view taken from the oval area 10 in FIG. 1.

The broken lines in the drawings depict portions of the telescope that form no part of the claimed design.
